145,285

DESIGN FOR A WHIRLIGIG TOY

John A. Brewer, Kalamazoo, Mich.

Application September 8, 1945, Serial No. 121,936

Term of patent 7 years

(Cl. D34—15)

To all whom it may concern:

Be it known that I, John A. Brewer, a citizen of the United States, residing at the city and county of Kalamazoo, State of Michigan, have invented a new, original, and ornamental Design for Whirligig Toy, of which the following is a specification, reference being had to the accompanying drawing, forming part thereof.

The figure is a perspective view of a whirligig toy, the opposite side being a substantial duplicate of the side presented, showing my new design.

I claim:

The ornamental design for a whirligig toy, as shown and described.

JOHN A. BREWER.
